(57) **CLAIM**

The ornamental design for a packaging, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a packaging;

FIG. 2 is a front view thereof;

FIG. 3 is a right side view thereof;

FIG. 4 is a back view thereof;

FIG. 5 is a left side view thereof;

FIG. 6 is a top view thereof;

FIG. 7 is a bottom view thereof.

FIG. 8 is a perspective view of a packaging;

FIG. 9 is a front view thereof;

FIG. 10 is a right side view thereof;

FIG. 11 is a back view thereof;

FIG. 12 is a left side view thereof;

FIG. 13 is a top view thereof;

FIG. 14 is a bottom view thereof.

FIG. 15 is a perspective view of a packaging;

FIG. 16 is a front view thereof;

FIG. 17 is a right side view thereof;

FIG. 18 is a back view thereof;

FIG. 19 is a left side view thereof;

FIG. 20 is a top view thereof;

FIG. 21 is a bottom view thereof.

(Continued)

FIG. 22 is a perspective view of a packaging;
 FIG. 23 is a front view thereof;
 FIG. 24 is a right side view thereof;
 FIG. 25 is a back view thereof;
 FIG. 26 is a left side view thereof;
 FIG. 27 is a top view thereof; and,
 FIG. 28 is a bottom view thereof.
 The broken lines shown are for the purpose of illustrating parts of the article forming no part of the claimed design. The white partial circle-shaped areas surrounding the colored portions do not form part of the claimed design.
